UNITED STATES PATENT OFFICE.

JABEZ HODSKINSON, OF SALEM, MASSACHUSETTS.

LEATHER-BLACKING MACHINE.

SPECIFICATION forming part of Letters Patent No. 322,606, dated July 21, 1885.

Application filed October 23, 1884. (No model.)

To all whom it may concern:

Be it known that I, JABEZ HODSKINSON, of Salem, in the county of Essex and State of Massachusetts, have invented certain Improvements in Machines for Blacking Leather, of which the following is a specification.

This invention has for its object to provide a machine adapted to rapidly and thoroughly apply blacking, paste, or other fluid or semi-fluid material to the surface of sheets of leather spread on a supporting-bed.

The invention consists, as a whole, in an organized machine composed of a bed or support for the leather, two slides or frames, each movable in two directions over said bed, each provided with a series of brushes adapted to bear simultaneously on the leather supported by the bed, each brush having a reservoir communicating with it for the material to be applied to the leather, and mechanism for reciprocating the two frames or slides longitudinally, and thereby causing the brushes to distribute the fluid over the surface of the leather, and mechanism whereby the frame may be moved laterally as the operator may desire to present the brushes to the different parts of the leather.

The invention also consists in certain details of construction, all of which I will now proceed to describe and claim.

Of the accompanying drawings, forming a part of this specification, Figure 1 represents a plan view of my machine. Fig. 2 represents a front elevation. Fig. 3 represents an end elevation. Fig. 4 represents an enlarged section on line $\alpha\alpha$, Fig. 1. Fig. 5 represents a view of a modification.

The same letters of reference indicate the same parts in all the figures.

In the drawings, a represents a bed or table supported by a suitable frame-work, b , and serving to support a sheet or sheets of leather to be coated with blacking or other material.

c represents a carriage located over the bed and extending the entire length thereof. Said carriage is adapted to travel on fixed cogged tracks $d d$, extending across the ends of the supporting-frame b , a shaft, e , provided at ends with pinions ff , meshing with the tracks d , being journaled in ears or bearings $g g$ on the carriage. The shaft e is provided with a hand-wheel, h , whereby the operator is enabled to

rotate it and thus move the carriage laterally over the bed by the engagement of the pinions ff with the cogged tracks $d d$. 55

$i i$ represent slides supported by the carriage e , and adapted to reciprocate lengthwise of the carriage. Said slides are reciprocated by means of a crank-shaft, jj , journaled in standards $k k$ at the ends of the carriage and connected by connecting-rods $j' j'$ with the slides $i i$, each shaft having two cranks, which project in opposite directions, so that the rotation of said crank-shaft will cause the slides to reciprocate simultaneously, but in opposite directions. Each slide supports a series of brushes, l , which are located below the slides, so that they can act on the leather on the bed a . Each brush has a tubular shank, m , which communicates with a reservoir, n , in which is placed a quantity of the blacking or other fluid to be supplied to the leather. There is, preferably, a separate reservoir for each brush, the reservoirs being supported by the slides. Each reservoir has a follower, o , which is pressed downwardly on the material by its weight, assisted by springs $p p$, if preferred. (See Fig. 2.) A sliding gate or valve, q , Fig. 4, shuts off the blacking or other material when the operator desires. The tubular shank of every alternate brush is adapted to rotate with the brush, and is provided with a pinion, r , (see Fig. 4,) which meshes with a rack, s , affixed to the carriage. (See Figs. 1 and 4.) The reciprocating movements of the slides cause the brushes that have the pinions r to rotate by the engagement of said pinions with the racks $s s$. 75 80 85

The crank-shafts jj are rotated to reciprocate the slides $i i$ by means of driving-shafts $t t$, journaled in fixed bearings on the frame of the machine and having pinions $u u$, which are adapted to slide along said shafts but are connected thereto by keys projecting into longitudinal grooves t in the shafts, so that the pinions will always rotate with the shafts, but are free to move with the carriage when it is moved laterally by the operator, as before described. The crank-shafts are provided with cog-wheels v , which mesh with the pinions u and receive motion therefrom. 90 95 100

The operation is as follows: The leather being in place on the bed, the operator brings the brushes to bear on the upper surface of

the leather, and then by means of the valve q allows a suitable quantity of blacking to flow from the reservoirs to the leather under the brushes. The driving-shafts t being then set 5 in motion, the slides are caused to reciprocate and thus cause the brushes to distribute the blacking over the surface of the leather, the rotation of the journaled brushes facilitating the distribution and making it more uniform.

10 When the leather under the carriage has been sufficiently blackened, the operator moves the carriage laterally, as above described, and thus presents the brushes to a different part of the leather, and thus the operation is continued until the entire surface of the leather has been 15 acted on. At the end of the operation the operator raises the portion of the carriage which supports the slides i , so as to separate all the brushes from the leather. This portion of the 20 carriage is movable vertically in the parts of the carriage that support the end standards, k , k . Vertical shafts a' , a' , having at their upper ends bevel-gears b' , b' , are journaled in the standards k , k , and are threaded at their lower 25 ends, said threaded ends engaging with threaded sockets formed in the vertically-movable portion of the carriage. A horizontal shaft, c' , c' , journaled in the standards k , k , has at its ends bevel-gears d' , d' , meshing with the 30 bevel-gears b' , b' . When the shaft c' is rotated, (by means of a hand-wheel, f' , affixed to it,) the shafts a' , a' are simultaneously rotated by the engagement of the bevel-gears, and are thus caused to either raise or lower the vertically-movable portion of the carriage. The 35 operator is thus enabled to elevate and depress all the brushes simultaneously.

Each brush is capable of independent vertical movement, and is pressed downwardly 40 by a spring, g' . (See Fig. 4.) The brushes are thus enabled to yield to inequalities in the surface of the leather, and to be raised and separated from the leather independently, if desired.

45 A lever, h' , Fig. 2, is preferably provided for each brush, said levers being engaged with the shanks of the brushes, the levers being pivoted to lugs on the slides i , i . When the outer end of a lever h' is depressed, the brush-shank engaged therewith is raised, as will be readily seen.

I do not limit myself to the described details of construction, but may modify the same variously without departing from the spirit 55 of my invention.

In Fig. 5 I have shown a modification of the mechanism for reciprocating the slides i and rotating the brushes. In this modification a driving-shaft, t , imparts motion through 60 bevel-gears to a vertical shaft, j' , this being geared to another shaft, k' , having at its lower end a crank, l' , which is connected by a rod, m' , with one of the slides i , and reciprocates the slide. The shaft k' has an eccentric pulley, 65 n' , which is belted to an eccentric pulley, q' , on the shank or arbor of one of the brushes l . The eccentricity of the pulley n' is such that

it will keep the connecting-belt tight while the slide is reciprocating. The arbor of the pulley o' is geared to the arbors of the other brushes 70 on the slide, so that all the brushes are rotated continuously. The brushes that are engaged with the racks s , s on the carriage are oscillated or rotated first in one direction and then in the opposite direction by the reciprocating 75 movements of the slides. I do not confine myself, however, to either mode of operation, but may either oscillate the brushes or rotate them continuously. If desired, all the brushes may be rotated instead of every alternate 80 brush, or all the brushes may be non-rotating.

Instead of providing a series of independent 85 reservoirs n , a single reservoir may be employed communicating with all the brushes. The reservoir or reservoirs may be on a support which is independent of the slides, the connection with the brushes being effected by flexible tubes.

The carriage may have one or any other desired number of slides instead of two. 90

I claim—

1. In a machine for applying blacking or other material, the combination of a supporting-bed having lateral guides, a carriage located over said bed and capable of lateral movement on said guides, a slide or slides supported by the carriage and capable of longitudinal movement thereon, a series of brushes supported by each slide, and mechanism, substantially as described, for reciprocating the 100 slide or slides, as set forth.

2. The combination of a supporting-bed having guides, a carriage located over said bed and movable laterally in said guides 105 on the carriage, and provided with a series of brushes, and a reservoir or reservoirs for the material to be applied communicating with said brushes, as set forth.

3. The combination of the supporting-bed, 110 the carriage, the slide or slides on the carriage, each provided with a series of brushes, and mechanism, substantially as described, whereby the slides and brushes may be simultaneously raised and lowered, as set forth. 115

4. The combination of the bed, the carriage, and the slide or slides on the carriage, and a series of brushes on each slide, each capable of an independent vertical movement, and provided with a holding-down spring, as 120 set forth.

5. The combination of the bed, the carriage, the slide or slides on the carriage, and a series of brushes on each slide, each capable of an independent vertical movement, and provided with a lever, whereby it may be raised, 125 as set forth.

6. The combination of a supporting-bed, a slide having a series of brushes located over said bed, and mechanism, substantially as described, for reciprocating said slides and brushes, as set forth. 130

7. The combination of the carriage, the slide or slides thereon, the brushes supported,

by the slides, and mechanism, substantially as described, for reciprocating the slides, and mechanism, substantially as described, whereby the brushes are rotated, as set forth.

5 8. The combination of the carriage, the two slides thereon, each having a series of brushes, and mechanism, substantially as described, whereby the slides are reciprocated simultaneously in opposite directions, as set forth.

10 9. The combination of the carriage having the shaft *e* and pinions *f f*, the supporting frame having the cogged tracks *d d*, the slide or slides on the carriage, having the brushes *l*, and mechanism, substantially as described, whereby said slides are reciprocated, as set forth.

10. The combination of the carriage having the racks *s s*, the slides having the brushes *ll*, provided on their shanks with pinions *r*, meshing with said racks, and mechanism, substantially as described, for reciprocating said slides, and thereby rotating the brushes, as set forth. 20

In testimony whereof I have signed my name to this specification, in the presence of two subscribing witnesses, this 17th day of October, 25 1884.

JABEZ HODSKINSON.
